US0D1098105S

(12) **United States Design Patent** (10) **Patent No.:** **US D1,098,105 S**
Luo (45) **Date of Patent:** **** Oct. 14, 2025**

(54) **COMPUTER MODULE**

(71) Applicant: **SUZHOU YUANKONG ELECTRONIC TECHNOLOGY CO., LTD.**, Suzhou (CN)

(72) Inventor: **Yuan Luo**, Suzhou (CN)

(73) Assignee: **SUZHOU YUANKONG ELECTRONIC TECHNOLOGY CO., LTD.**, Suzhou (CN)

(**) Term: **15 Years**

(21) Appl. No.: **29/891,498**

(22) Filed: **May 5, 2023**

(30) **Foreign Application Priority Data**

Nov. 8, 2022 (CN) 202230743626.7

(51) **LOC (15) Cl.** **14-02**

(52) **U.S. Cl.** USPC **D14/313**; D14/301

(58) **Field of Classification Search**

USPC D14/140.2–140.4, 300–302, 308, D14/311–314, 348, 353–355, 444–446, D14/450, 500–505; D13/103, 110, 112, D13/122, 158–160, 184; D21/324, 515

CPC G11B 33/02; G11B 33/128; G06F 1/20

See application file for complete search history.

(57) **CLAIM**

The ornamental design for a computer module as shown and described.

DESCRIPTION

FIG. 1 is a front perspective view of a computer module showing the claimed design;

FIG. 2 is a front view thereof;

FIG. 3 is a rear view thereof;

FIG. 4 is a top view thereof;

FIG. 5 is a bottom view thereof;

FIG. 6 is a left view thereof; and,

FIG. 7 is a right view thereof.

All of the broken lines illustrate portions of the computer module that form no part of the claimed design.

1 Claim, 7 Drawing Sheets
